US00D918247S

(12) **United States Design Patent** (10) Patent No.: **US D918,247 S**
Quandt (45) Date of Patent: **** May 4, 2021**

- (54) **DISPLAY SCREEN OR PORTION THEREOF WITH GRAPHICAL USER INTERFACE**

(71) Applicant: **Apple Inc.**, Cupertino, CA (US)

(72) Inventor: **Thorsten Quandt**, Hamburg (DE)

(73) Assignee: **Apple Inc.**, Cupertino, CA (US)

(**) Term: **15 Years**

(21) Appl. No.: **29/725,871**

(22) Filed: **Feb. 27, 2020**

Related U.S. Application Data

- (63) Continuation of application No. 29/622,292, filed on Oct. 16, 2017, now Pat. No. Des. 879,810, which is a continuation of application No. 29/515,146, filed on Jan. 20, 2015, now Pat. No. Des. 803,880.

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

Once upon request and payment of the necessary fee. The sole FIGURE shows a display screen or portion thereof with graphical user interface showing my new design.

The peripheral dashed broken line illustrates a display screen or portion thereof, and forms no part of the claimed design.

The dashed broken lines within the peripheral dashed broken lines represent text or features which form no part of the claimed design.
